UNITED STATES PATENT OFFICE.

JOHN HENRY FAULKNER, OF LONDON, ENGLAND.

CONVERTIBLE CABINET, CASE, OR THE LIKE.

1,090,524.

Specification of Letters Patent. Patented Mar. 17, 1914.

Application filed July 7, 1911. Serial No. 637,317.

To all whom it may concern:

Be it known that I, JOHN HENRY FAULKNER, a subject of the King of England, residing at 31 Langland Gardens, Hampstead, London, N. W., England, have invented new and useful Improvements in Convertible Cabinets, Cases, or the like, of which the following is a specification.

This invention relates to improvements in portable convertible cabinets, cases or the like of the kind which may be converted into a table and one or more seats.

According to this invention, the cabinet or case comprises bottom and side portions hinged together so as to be opened out to form a table top, folding legs pivoted to the underside of the bottom to serve as a support, and a removable lid fitted with folding legs to form a seat or seats, with or without additional seats adapted to be contained in the cabinet.

The cabinet or case may be made from any suitable material, for instance, wood, compressed cane, or metal.

The invention may be used for various purposes in which it is desired to carry articles from place to place and to provide when required a table and seats which may be readily erected by manipulating the cabinet or case. I will describe my invention as applied to a cabinet or case which may be packed with the requisites for a luncheon or picnic, and I have shown in the accompanying drawings a convertible cabinet which may be conveniently carried on the side step of a motor car.

Figure 1 is a perspective view with certain parts opened out to form a table; Fig. 2 is a perspective view of a seat formed by one portion of the lid of the cabinet; Fig. 3 is a view showing the underneath of the cabinet with the parts folded up; Fig. 4 is an underneath view of the other portion of the lid forming a second seat, with the parts folded up; Fig. 5 is a part perspective view of the seat shown in Fig. 2 with parts unfastened, and Fig. 6 is an elevation, partly in section, showing one of the ends of the cabinet opened out.

The cabinet comprises a bottom A, folding sides B, ends C and lid D, D¹. The sides B are connected to the bottom A by hinges A¹ of a known kind in such a manner that the sides may be folded down so as to occupy the extended position shown in Fig. 1 and be supported in that position.

The ends C may be fixed to the bottom A so as to remain in an upright position or may be hinged thereto so as to be folded down in a similar manner to the sides B. In Fig. 6 the end C is shown opened out. It is connected to the bottom A by butt hinges A² similar to the hinges A¹. A compartment E is provided on the inside of each end C. This compartment is fitted with a drawer F which may be pulled out from either side and has recesses F¹ in its ends for that purpose. The folding ends may be secured in an upright position by any suitable means. In Figs. 1 and 6 a sliding catch E¹ is recessed into the bottom A, a projection E² on the compartment E co-operating therewith. The sides B are provided with catches B¹ which engage spring clips C¹ on the ends C to secure the sides in their folded up position. The ends C have drop handles C² for convenience in carrying the apparatus.

Folding legs G are pivoted by pins G¹ to brackets G² recessed into and secured to the underneath side of the bottom A. The legs G may be folded up as shown in Fig. 3 and secured in that position by clips G³ fastened to the bottom A. The legs G are splayed outward but have sufficient spring to permit of their being sprung inward and passed beneath the clips G³. The legs will be securely held in the clips G³ by reason of their tendency to spring outward. Brackets H are secured to and recessed in the bottom A, and on pins H¹ of these brackets are pivoted stays J. At the ends of the stays J blocks J¹ are pivoted on pins J² which lie in a plane parallel to the pins H¹. Struts K are pivoted to the blocks J¹ so as to turn on an axis at right angles to the pins J². The bottom A is recessed so that the struts K, when the stays J are folded up, may lie flush with the outer surface of the bottom. The stays J and struts K are secured in their folded position by pivoted catches L. Short legs A³ of a height sufficient to support the cabinet with the folded legs and stays clear of the step or other place upon which the cabinet may be rested, are secured at each corner of the bottom A. These legs A³ may be faced with rubber or may be in the form of rubber stops. The ends of the struts K are reduced to form shoulders K¹, and the reduced portions K² are of square or other polygonal cross-section. The legs G have holes G⁴ of a shape corresponding to that

of the reduced portions K^2 , and the reduced portions K^2 engage the holes G^4 when the stays J are opened out and the struts K fixed in position to secure the legs G in their opened out position. The reduced portions K^2 may be tapered slightly to facilitate their insertion in the holes G^4 . The squared ends of the struts K prevent them turning in the holes G^4 , and the parts are thus held more rigid.

10 The lid of the cabinet may form one or more seats which fit the table. In the example given in the drawings the lid is in two portions D , D^1 and each portion may be utilized as a seat as will now be explained.

15 To the underside of the lid portions D , D^1 are pivoted legs M and stays N with struts O , and the arrangement is similar to that of the legs G , stays J and struts K on the bottom of the cabinet as already described.

20 The legs M are pivoted to brackets M^1 recessed in the portions D and D^1 . The legs M , when folded up, do not lie within each other as do the legs G as they are shorter and fold up toward each other as clearly

25 shown in Fig. 4. They are secured in their folded position by clips M^2 . The stays N are pivoted to brackets N^1 recessed in the lid portions and the struts O are pivoted to blocks O^1 on the ends of the stays N so as to be turned either into the folded position shown in Fig. 4 or into the opened out position shown in Fig. 2. When in the folded position they may be secured by pivoted

30 35 catches O^2 . The ends O^2 of the struts O are squared to fit corresponding holes in the legs M .

The lid portions D , D^1 are secured to the ends C of the cabinet by means of projecting catches D^2 at one end which fit into holes D^5 in one end C . The other end C has spring clips D^3 which engage catches D^6 on the opposite end of the lid portions D , D^1 . The two portions D , D^1 are scarfed together at D^4 as shown in Fig. 3. This arrangement prevents wet from entering the cabinet at the joint.

40 45 50 When the cabinet or case is folded up it forms a convenient receptacle for various articles. The cabinet illustrated in the drawings may be fitted with a luncheon basket which would occupy the space between the bottom A , lid D , D^1 and end compartments E . When it is desired to convert the cabinet into a table and seats, the legs G are released from the clips G^3 and opened out, and the pivoted catches L are turned so as to release the stays J and struts K . The struts K are then turned so as to occupy the position indicated in Fig. 1 and their reduced ends are inserted in the holes G^4 in the legs. The length of the struts K is such that the legs G are forced against the shoulders K^1 of the struts by reason of the spring of the legs G .

55 60 65 The lid portions D , D^1 are removed by re-

leasing their catches O^6 and sliding them a short distance longitudinally. The sides B are released by pressing the spring clips C^1 and are opened out into a horizontal position. The ends C , when they are hinged to the bottom A , may also be opened out as shown in Fig. 6. The luncheon basket, etc., may now be removed and the parts will then form a convenient table. The legs M on the lid portions are opened out and secured in position in a similar manner to the legs G , and in their opened out position form a seat as clearly shown in Fig. 2.

70 It will be understood that various modifications may be made in the construction of the parts without departing from the spirit of the invention. For example the lid may be in one piece and form only one seat. The compartments E and drawers F may be dispensed with, or other compartments fitted as 80 may be desired. Further, the sides B and ends C may be hinged in any other suitable manner which will enable them to be folded down and supported in a horizontal position.

90 95 Where the lid is in a single piece and forms only one seat, a further seat or seats may be provided constructed substantially the same as those above described but being somewhat smaller so as to fit inside the cabinet. These extra seats may conveniently rest on the compartments E , which of course would be of suitable dimensions to permit the insertion of the additional seats.

100 What I claim as my invention and desire to secure by Letters Patent is:—

1. A combined box and table comprising a sectional table top, the members of which are adapted to be adjusted to form opposite sides and bottom of a box-like case or to be 105 arranged in horizontal alignment, legs pivotally connected with the member constituting the bottom of the box to fold against the outer surface thereof, stays pivotally connected to the same member, and struts 110 pivotally connected to the stays whereby they may extend parallel with the stays or transversely thereof, each strut when in the last said position being adapted to engage two of the legs.

115 120 125 130 2. A combined box, table and seat comprising a member which constitutes the bottom of the box and midsection of the table top, two members hinged to opposite edges of the first said member and adapted to be adjusted into horizontal alignment therewith to form a table top or into position at an angle thereto to form sides of the box, legs pivotally connected with and adapted to fold against the lower face of the member constituting the bottom of the box, a lid or cover for the box, and legs connected with and adapted to fold against the inner face of the lid.

3. A combined box and table comprising 130

a sectional table top having its members connected so that they may be adjusted to form opposite sides and the bottom of a box or be held in horizontal alinement, legs pivotally connected with and adapted to fold beneath the member forming the bottom of the box, stays similarly connected with said member, a strut connected with each stay by means permitting it to be turned into alinement with or at right angles to the stay, the ends of each strut being reduced and

adapted to enter apertures in two of the legs when the latter are positioned for use and the strut extends at right angles to its supporting stay.

15

In testimony whereof I have signed my name to this specification in the presence of two subscribing witnesses.

JOHN HENRY FAULKNER.
